(57) **CLAIM**

The ornamental design for a package for flexible pipes and flexible hoses, as shown and described.

DESCRIPTION

FIG. 1.1 is a bottom view of a package for flexible pipes and flexible hoses, showing my new design;

FIG. 1.2 is a top, front, right-side perspective view thereof;

FIG. 1.3 is a right-side view thereof;

FIG. 1.4 is a front view thereof;

FIG. 1.5 is a back view thereof;

FIG. 1.6 is a top view thereof; and

FIG. 1.7 is a top, back, left-side perspective view thereof.

The broken lines shown in FIGS. 1.2, 1.3, 1.6, and 1.7 encompass features of a handle attached to the package and form no part of the claimed design.

1 Claim, 7 Drawing Sheets
